UNITED STATES PATENT OFFICE

2,185,462

CIGARETTE AND CIGAR EXTINGUISHING
DEVICE

John H. Homrighous, Oak Park, Ill.

Application March 2, 1938, Serial No. 193,522

19 Claims. (Cl. 131—256)

This invention relates in general to cigarette and cigar extinguishing devices, and more in particular to devices of this character in which a pressing member may be operated to squeeze the burning ends of cigarettes and cigars and which include means for discarding the butts in an ash receptacle.

The discarding of lighted cigarettes creates a very dangerous fire hazard, and also causes considerable unnecessary smoke and odor when the lighted cigarettes are placed in an open ash tray without smothering.

It is one of the objects of this invention therefore to provide a small economical extinguishing device that can be used with any type of ash tray for quickly squeezing the burning ends of cigarettes and cigars to extinguish them.

Another object is to provide an extinguishing device that automatically ejects cigarettes and cigar butts into an ash tray after squeezing the ends of the lighted butts.

Other objects and advantages of this invention will appear from the following description and by the claims appended thereto, reference being had to the accompanying drawing, in which:

Figure 1 is a front elevation of the extinguishing device showing a number of parts with portions cut away.

Figure 2 is a cross-sectional view taken approximately on line 2—2 of Figure 1.

Figure 3 shows a detachable support.

In the drawing, 4 represents the frame, having pivoted near the base pressing members or levers 5 and 6. The levers 5 and 6 are shown pivoted on separate axes, but may be pivoted together on a common axis, or one of the levers may be stationary or a part of the frame. Each lever is extended inwardly for a portion of its length so that the projected surfaces will form a wedge shaped opening of such size that it will hold a lighted cigarette or cigar when inserted with a slight pressure, the wide gap in the levers above the wedge shape opening facilitating this operation. These levers are adapted to be brought together to crush the cigarette butt by squeezing between the fingers of the operator. When the pressure is released the levers are returned to normal by springs, one shown at 7, and are held in normal position by stops 8 and 9, parts of the frame 4.

The butt is ejected by the action of the ejecting member or bar 10, which is pivoted in a direction transverse to that of the levers near the top of frame 4 and extends preferably down below the small wedge shaped opening between the

levers. This ejecting bar 10 may be manually operated by pressure near the top in a transverse direction to that of levers 5 and 6, or as shown in the drawing, it may be automatically operated thru the action of the arm 11, secured to lever 5 at its axis, and the small spring wire clip 12, secured to the upper part of ejecting bar 10. The arm 11 passes over clip 12, when lever 5 is moved toward lever 6, and under the clip 12 when returning to normal, thereby forcing the ejecting bar 10 between the levers 5 and 6. The return to normal of bar 10 is controlled through the action of spring 13 and stop 14, and the distance of travel of bar 10 is limited by the lug 15 contacting the top of the frame 4.

It is desirable in certain instances to provide some method for closing the opening at the side of the pressing members opposite the ejecting bar so that the lighted butts may be dropped in the device without falling out and also to prevent the ejector bar from throwing the butts outward too far. To accomplish this feature, the closing plate 16 is supported opposite the ejecting bar 10 by rod 17 which is fixedly secured to the lower extremities of the bar 10 and plate 16 whereby any movement of the bar 10 will likewise cause the closing plate 16 to follow. The plate 16 is shown in a partially operated position by the dotted lines.

The upper portion of frame is bent over, as shown in Figure 2, to form a support for hanging the device on a match box or for placing it in certain types of ash trays.

The small disk support 18, which may be part of the frame or welded thereto, is preferably secured to the base by a screw as shown so that it can be easily detached. By the use of this disk support the device will set in an upright position inside of an ash tray. In Figure 3 there is shown a small pin support which may be screwed into the under side of frame 4 in place of support 18, in order to adapt the device to fit certain other types of ash trays.

It is obvious that the extinguishing device may take a variety of other shapes or forms without departing from the essential principles thereof. Therefore I do not desire to be limited to the particular form shown herein, but contemplate all modifications and changes therein, within the terms of the appended claims.

Having thus described my invention, I claim:

1. In an article of manufacture, the combination comprising a frame, pressing members pivoted to said frame, and an ejecting bar pivoted in a transverse relation to said pressing members,

- said ejecting bar extending throughout a portion of the length of said pressing members.
2. In an article of manufacture, a frame, a pair of levers pivoted to said frame, and an ejecting bar pivoted to said frame and extending throughout a portion of the length of said levers.
3. An article of manufacture comprising a frame provided with a support, levers pivoted to said frame, each of which has a projecting surface, and an ejecting bar pivoted to said frame and extending throughout and beyond the length of the said projecting surfaces.
4. An article of manufacture comprising a frame, a pair of levers pivoted to said frame, and an ejecting bar pivoted to said frame in a transverse relation to said levers, said ejecting bar having a closing plate secured thereto.
5. An article of manufacture comprising a frame, a pair of levers pivoted to said frame, and an ejecting bar pivoted to said frame and having a closing plate secured thereto, the said ejecting bar extending throughout the length of said pressing levers.
6. An article of manufacture comprising a frame provided with a support, a pair of levers pivoted to said frame, each of which has a projecting surface, an ejecting bar pivoted to said frame and extending throughout and beyond the length of the said projecting surfaces, and an arm secured to one of said levers arranged to automatically operate said ejecting bar.
7. An article of manufacture comprising a frame, a pair of levers pivoted to said frame, an ejecting bar pivoted to said frame and having a closing plate secured opposite thereto, and an arm secured to one of said levers arranged to automatically operate said ejecting bar.
8. In an article of manufacture, the combination of a pressing member with an ejecting member extending throughout a portion of the length of said pressing member, and means cooperating with the said members to transmit motion to the said ejecting member in a direction transverse to that of the said pressing member.
9. In an article of manufacture, the combination of pressing members with an ejecting bar extending throughout a portion of the length of said pressing members, and an arm secured to one of said members, whereby motion may be transmitted to the said ejecting bar in a direction transverse to that of the said pressing members.
10. An article of manufacture comprising a frame, a lever pivoted to said frame, and an ejecting bar pivoted in a transverse relation to said lever, said ejecting bar extending lengthwise of said lever.
11. An article of manufacture comprising a frame, a lever pivoted to said frame, and an ejecting bar pivoted to said frame in a transverse relation to said lever, said ejecting bar extending lengthwise of said lever.
12. An article of manufacture comprising a frame, a lever supported on said frame, an ejecting bar supported in a transverse relation to said lever, and a closing plate supported opposite said ejecting bar and extending throughout a portion of the length of said lever.
13. An article of manufacture comprising a frame, a lever supported on said frame, an ejecting bar supported in a transverse relation to said lever, a closing plate supported opposite said ejecting bar and extending throughout a portion of the length of said lever, and an arm secured to said lever, arranged to automatically operate said ejecting bar.
14. An article of manufacture comprising a frame, a pressing member supported on said frame, an ejecting member supported in a transverse relation to said pressing member, a closing plate supported opposite said ejecting bar and extending throughout a portion of the length of said members, and means cooperating with said members to transmit motion to the said ejecting member in a direction transverse to said pressing member.
15. An article of manufacture comprising a frame provided with a disk support, a lever pivoted to said frame, an ejecting bar pivoted in a transverse relation to said lever, a closing plate opposite said ejecting bar and extending throughout a portion of the length of said lever, and means for operating said ejecting bar.
16. An article of manufacture comprising a frame, provided with a disk support, a pair of levers pivoted to said frame, an ejecting bar pivoted in a transverse relation to said levers, a closing plate mounted opposite and extending lengthwise of said ejecting bar, and means for operating said ejecting bar.
17. An article of manufacture comprising a frame, a pressing member supported on said frame, and an ejecting member secured to said frame, the said ejecting member extending throughout and beyond the length of said pressing member.
18. In a cigarette extinguishing device, means for receiving and crushing the lighted end of a cigarette butt, said means including a manually operable member, and means for automatically ejecting the said butt responsive to the release of said member.
19. In a cigarette extinguishing device, a pair of normally open jaws adapted to receive a lighted cigarette butt between them, manually operable means for closing said jaws sufficient to crush said butt, means for opening said jaws when the said first means is released, and means for ejecting the butt from between said jaws.

JOHN H. HOMRIGHOUSE. 80
